William P. Gray of Penn Township, Pa.
Assignor to
Abram & Joseph Cox of Philadelphia, Pa.
Letters Patent No. 597. — Dated Sept. 6th, 1853.

—————
The schedule referred to in these Letters Patent, and making part of the same.

Mar. 29 /

To all whom it may concern:

Be it known, that I, W. P. Gray of Town District in the County of Philadelphia, and State of Pennsylvania, have produced a new and original design in stoves, called
"The Model Parlor Cook,"

and I do hereby declare that the following is a full, clear, and exact description of the same, reference being had to the annexed drawings, forming a part of this specification, in which-

Figure 1 is an elevation of Back plate.

Figure 2, a similar view of Front plate, and

Figure 3, an elevation of Side plate.

Symmetrical designs have but one half of their details given.

The Back plate A, which is of the form indicated by the section on line xx of figure 1, is occupied by the panels B, C, D, and E; the former sunken and surrounded with the moulding a, (seen in section xx fig. 1,) and the latter also sunken, and enclosed by the bead b. The panels C, are enclosed with a moulding c, similar to the moulding a, and like all the panels on the plate are of a gothic form. The panel D bears the inscription

"The Model Parlor Cook, A. & J. Cox, Phil'a."

in raised capitals; the bead d encloses the panel. The panels B, C, E, are ornamented by the beads e and f, which crossing at right angles, divide the surfaces of the panels into the square cells i. On the sides of the plate are panels F, enclosed by the bead h. The details of arrangement of the several panels and mouldings are fully set forth in fig. 1.

The front plate G has the form of the plate A, and bears the panels H, I, and J, similar to, and enclosed as the panels D, E, and F of the back plate. In the upper portion of the plate are the oven doors P, in form, ornament, and mouldings the same as the panels C. The lower feed doors R are ornamented by the gothic moulding m, the same as the moulding a of the panel B. The panels are vacant for filling with mica, or other substance. The details of arrangement are set forth in figure 2.

The side plates S are of the form shown in the section on y.y, of figure 3, bearing the two gothic panels T, surrounded by the moulding r, and ornamented with the cells s like those on the panels of the other plates, the configuration and arrangement of parts being fully set forth in figure 3.

The upper and lower portions of the several plates are ornamented with the mouldings W and V, made up and arranged as shown in the drawings, so as to

form a base and cornice to the plates. On the moulding w. of the front and side plates is the inscription "Pat'd. 1853" in raised capitals and numerals, arranged as set forth in figures 2 and 3.

What I claim as my invention or production, and desire to secure by Letters Patent, is

The design, configuration, and arrangement of the mouldings, panels and ornaments on the front, back, and side plates of the stove called "The Model Parlor Cook" as fully set forth in this specification and annexed drawings.

In testimony whereof, I have hereunto signed my name before two subscribing witnesses.

Witnesses,

L. Brazer,
James Alexander.

W. D. Gray.
